(57) **CLAIM**

The ornamental design for a saddle, as shown and described.

DESCRIPTION

FIG. 1 is a front perspective view of a saddle showing my new design;

FIG. 2 is a top view thereof;

FIG. 3 is a front view thereof;

FIG. 4 is a rear view thereof;

FIG. 5 is a right side view thereof;

FIG. 6 is a left side view thereof;

FIG. 7 is an enlarged view of FIG. 2 showing a junction zone between the skirt and knee block of the saddle;

FIG. 8 is an enlarged side view of FIG. 6 showing the junction zone between the skirt and knee block with the knee block in a first state (forward position);

FIG. 9 is an enlarged side view of FIG. 6 showing the junction zone between the skirt and knee block with the knee block in an alternative state (intermediate position);

FIG. 10 is an enlarged side view of FIG. 6 showing the junction zone between the skirt and knee block with the knee block in a second alternative state (angled position); and, FIG. 11 is an enlarged side view of FIG. 6 showing the junction zone between the skirt and knee block with the knee block in a third alternative state (rearward position).

The dot-dash style broken lines represent a boundary of the claim and forms no part thereof. The even-length broken lines depicting the remainder of the saddle form no part of the claimed design.
